COFFEE MEASURING CUP

Stephen Gerlich, 5320 S. Albany Ave.,
Chicago, Ill. 60632

Filed June 7, 1968, Ser. No. 12,264

Term of patent 14 years

Int. Cl. D7—03; D10—08

U.S. Cl. D44—29

FIG. 1 is a top perspective view of a coffee measuring cup embodying my new design;

FIG. 2 is a bottom perspective view;

FIG. 3 is a side elevational view;

FIG. 4 is a front elevational view; and

FIG. 5 is a rear elevational view.

I claim:

The ornamental design for a coffee measuring cup, substantially as shown.
